UNITED STATES PATENT OFFICE.

WILLIAM H. LEONARD AND SULLIVAN V. JOHNSON, OF DENVER, COLORADO, ASSIGNEES
TO THE DENVER ROCK DRILL MANUFACTURING COMPANY, OF DENVER, COLORADO,
A CORPORATION OF COLORADO.

TOOL-RETAINER.

1,307,911.

Specification of Letters Patent. Patented June 24, 1919.

Application filed May 25, 1917. Serial No. 170,977.

To all whom it may concern:

Be it known that we, WILLIAM H. LEONARD and SULLIVAN V. JOHNSON, citizens of the United States, residing at Denver, in the county of Denver and State of Colorado, have invented certain new and useful Improvements in Tool-Retainers, of which the following is a specification.

The present invention is directed to improvements in tool retainers, and while more particularly designed for use on drilling apparatus, it will be of course obvious that it is not necessarily limited thereto.

One of the primary objects of the invention is to provide a novel and simple retainer so fashioned that the resiliency thereof will serve to permit its movement under strain and secure its automatic return to its normal position when released.

Still another and important object of the invention is to provide means whereby when the retainer is moved forwardly under the action of the tool it will be positively locked against pivotal movement, and consequently prevent the retainer from accidentally disengaging the tool.

In the drawings:

Figure 1 is a perspective view of the device.

Fig. 2 is a top plan view.

Fig. 3 is a side elevation with the retainer locked in its operative position.

Fig. 4 is a side elevation with the retainer in its inoperative position.

Fig. 5 is a detail longitudinal sectional view through one of the pivot connections and the adjacent parts.

Fig. 6 is a cross sectional view.

Similar reference numerals designate corresponding parts in all the figures of the drawings.

Referring to the drawings, 1 designates a head which constitutes a holder for receiving the drill steel 2, said steel being provided with the usual collar 3. Upon diametrically opposite sides of the holder are formed lugs 4, the same being provided with forwardly and outwardly inclined faces 5. These lugs are further provided with

50 sockets 6.

The retainer comprises a yoke 7, which is formed from resilient metal, preferably round in cross section, said yoke having a lateral open loop 8 adapted to embrace the

steel 2, but of such size as to prevent the 55 collar 3 from passing therethrough.

The side arms 9 of the yoke have their ends provided with heads 10, the inner sides of which are formed with inclined faces 11 corresponding to the faces 5 on which they 60 are slideable.

The yoke 7 is formed of resilient metal, and it is therefore obvious that the faces 11 will be yieldably pressed against the faces 5, but at the same time permit the 65 heads 10 to slide thereon. For instance when strain is applied to the yoke incident to the engagement of the collar 3 with the loop 8, the heads 10 will slide forwardly, and owing to the presence of the inclined faces 5 and 11, said heads will spread outwardly. Upon the yoke being relieved from the strain, the heads will automatically move toward each other owing to the tendency of the arms 9 to contract, thus causing the heads to slide rearwardly and returning the yoke to its normal position. 70

The lugs 4 are provided with stops 12, said stops having beveled rear sides 13, which are adapted, when the yoke has 80 moved forward, to interlock with beveled shoulders 14 formed on the heads 10. When the stops 12 and shoulders 14 are interlocked, as shown in Fig. 3 of the drawings, it is obvious that the yoke will be positively prevented from swinging to its open 85 position, thereby preventing the loop 8 from accidentally disengaging the steel collar 3.

The heads 10 are formed with longitudinal slots 15, said slots being slidably engaged with headed pivot pins 16. These pins are set in the sockets 6, and retained therein by transverse pins 17. In this manner the heads 10 are slideable and pivotally 90 connected with the lugs 4. It will be noted that the slots 15 are of such length that the stops 12 and shoulders 14 will interlock, thus preventing the rear walls of the slots 15 from engaging the pins 16, and by so 100 doing, no strain incident to the engagement of the yoke with the steel, will be imparted to the pins 16.

The lugs 4 are further provided with recesses 18, in which the side arms 9 of the 105 yoke snap, thus preventing the yoke from swinging accidentally to an open position. It will be obvious of course that the stops

12 will prevent the yoke 7 from swinging in one direction beyond its operative position, but the yoke can be readily swung in a reverse direction to a position free of the 5 tool, upon exerting slight pressure thereon.

Assuming that the yoke 7 is in the position shown in Fig. 2, at which time the collar 3 is disengaged from the loop 8, it 10 is obvious that the steel 2 will be permitted to operate in the usual manner, and that the heads 10 will be in their rearmost position. Now should the collar 3 engage the loop 8 and impart pressure thereto the head 10 will slide forwardly until the stops and 15 shoulders 12 and 14, respectively are interlocked, as shown in Fig. 3, thereby preventing the yoke from swinging in either direction. As soon as a strain is released from the loop the tendency of the heads 10 to 20 move toward each other will cause said heads to slide rearwardly on the lugs 4 owing to the presence of the mutually engaged inclined faces 5 and 11. As the heads 10 slide rearwardly it is obvious that the 25 shoulders 14 will disengage the stops 12, and the forward walls of the slots will engage the pins 16, thus limiting the rearward movement of said heads. When the 30 heads 10 have reached the limit of their rearward movement the yoke 7 can be swung to open the device, so that the tool or steel can be readily removed or replaced in the holder. This is readily accomplished since the heads 10 when in their 35 rearmost position are so located that the shoulders 14 can swing past the stops 12, and assume the position as shown in Fig. 4. To close the yoke it is only necessary to swing the same in a reverse direction and 40 until the side arms 9 thereof snap into the recesses 18.

From the foregoing, it is thought that the construction, operation and many advantages of the herein described invention 45 will be apparent to those skilled in the art, without further description, and it will be understood that various changes in the size, shape, proportion and minor details of construction may be resorted to without departing from the spirit or sacrificing any of the 50 advantages of the invention.

Having thus fully described my invention, what I claim as new, and desire to secure by Letters Patent, is:-

55 1. In apparatus of the character set forth, the combination with a tool holder, of a tool retainer bodily movable longitudinally of the tool holder, and means operating transversely of the tool holder for yieldingly resisting the bodily longitudinal movement of the tool retainer.

60 2. In apparatus of the character set forth, the combination with a tool holder, of a tool retaining yoke having laterally yielding side arms that are movable longitudinally

nally of the tool holder, and means for causing the spreading apart of the arms when the yoke is moved longitudinally in one direction.

65 3. In apparatus of the character set forth, the combination with a tool holder, of a tool retaining yoke having laterally yielding side arms that are movable longitudinally of the tool holder, and means for causing the spreading apart of the arms when the yoke is moved longitudinally in one direction, said arms automatically returning toward each other and to normal position when the yoke is moved longitudinally in the opposite direction. 70

75 4. In apparatus of the character set forth, the combination with a tool holder, of a tool retaining yoke having laterally yielding side arms that are movable longitudinally of the tool holder, and means for causing the spreading apart of the arms when the yoke is moved longitudinally forward and automatically returning them toward each other to normal position when the yoke is moved rearwardly. 80

85 5. In apparatus of the character set forth, the combination with a tool holder, of a tool retaining yoke having laterally yielding side arms that are movable longitudinally of the tool holder, and means on the holder and arms for permitting the bodily forward and backward movement of the yoke and causing its side arms to spread apart and resist such forward movement and automatically to move toward each other and return to a predetermined rear position when released. 90

95 6. In apparatus of the character set forth, the combination with a tool holder, of a tool retainer having an inclined bearing disposed longitudinally of the tool holder and to the line of strain imparted to the retainer, said tool retainer moving on said bearing when engaged by a tool and being automatically returned when released. 105

110 7. In apparatus of the character set forth, the combination with a tool holder having an outwardly and forwardly inclined bearing, of a tool retainer longitudinally slidable upon said bearing, said bearing constituting means for resisting the forward movement 115 of the tool retainer, said tool retainer automatically acting to be returned thereby when released.

120 8. In apparatus of the character set forth, the combination with a tool holder having oppositely disposed forwardly and outwardly inclined bearing surfaces, of a tool retainer comprising a yoke having yielding side arms that bear upon said surfaces, the resiliency of said side arms and the inclination of the surfaces being such that they will afford resistance to the forward movement 125 of the tool retainer and will automatically return the tool retainer to a rearward position when moved forwardly and released. 130

9. In apparatus of the character set forth, the combination with a tool holder, of a tool retaining yoke having laterally yielding side arms that are pivotally and longitudinally 50
5 slidable upon the tool holder, and means for causing the spreading apart of the arms when the yoke is moved longitudinally in one direction.
10. In apparatus of the character set forth, the combination with a tool holder having outstanding pivots, of a tool retaining yoke having side arms provided with longitudinal slots through which the pivots pass, and means for yieldingly maintaining 55
10 the yoke in its rearward position with the pivots in the front ends of the slots.
11. In apparatus of the character set forth, the combination with a tool holder having forwardly and outwardly inclined 60
20 bearing surfaces and outstanding pivots projecting from said surfaces, of a tool retainer comprising a yoke having side arms provided with longitudinal slots, said side arms being of yielding material and having
25 friction bearing on the surfaces, said side arms furthermore being provided with longitudinal slots through which the said pivots pass.
12. In a device of the class described, a 65
30 tool holder, of a tool retaining member formed from resilient metal, and slidably and pivotally connected with the holder, and means operable by the lateral contraction of the member to bodily move and yieldingly
35 maintain the latter in a predetermined position.
13. A device of the class described, a tool 70
40 holder having inclined faces associated therewith, a tool retaining yoke having its side arms provided with heads, said heads having inclined faces for slidably and yieldingly engaging the first named faces, said faces constituting means for normally maintaining the yoke in a predetermined position
45 and returning it thereto when removed therefrom.
14. In a device of the class described a tool holder, a tool retaining yoke having laterally resilient side arms, said arms being slidably and swingingly mounted on the 75
50 holder, the lateral inherent resiliency of the arms serving to hold the yoke in its normal position and to return the same to such position after disengagement with a tool.
15. In apparatus of the character set 80
55 forth, the combination with a tool holder, of a tool retainer pivoted on the holder to swing to and from a position to be engaged by a tool, and means in advance of the pivotal connection for positively locking the retainer against movement from said position when engaged by a tool, while permitting its movement when disengaged by the tool.
16. In apparatus of the character set 85
60 forth, the combination with a tool holder, of a tool retainer pivoted at its rear end on the tool holder and movable from and to a position to be engaged by a tool and also capable of movement longitudinally of the tool holder when engaged by a tool, and means in advance of the pivot for positively locking the retainer against movement from said position when engaged and moved by a tool while permitting its movement when disengaged by the tool.
17. In a device of the class described, a tool holder, a tool retaining yoke pivotally and slidably mounted on the holder, and projections respectively on the yoke and holder in advance of the pivotal mounting 90
80 that interlock upon the forward movement of the yoke to prevent the swinging movement of said yoke and disengage upon the rearward movement of the yoke to permit the swinging of said yoke.

85
In testimony whereof, we affix our signatures in the presence of two witnesses.
